UNITED STATES PATENT OFFICE.

MILLARD F. BROWN, OF KANSAS CITY, MISSOURI.

DESIGN FOR A CHEST OR BIN.

SPECIFICATION forming part of Design No. 29,439, dated October 4, 1898.

Application filed June 10, 1898. Serial No. 683,131. Term of patent 14 years.

To all whom it may concern:

Be it known that I, MILLARD F. BROWN, a citizen of the United States, residing at Kansas City, in the county of Jackson and State 5 of Missouri, have invented and produced a new and original Design for Chests or Bins, of which the following is a specification, reference being had to the accompanying drawing, forming part thereof.

10 The drawing represents a perspective view of a chest or bin, showing my new design, and the leading or material feature of the same comprises the following elements, viz: a large vertical cylinder having a conical or arched 15 top, a pair of much smaller vertical cylinders flanking the large cylinder and arranged slightly forward thereof and provided with flat caps, and a series of more diminutive cylinders arranged in a curved line in front of 20 the largest cylinder and between the two flanking cylinders, said diminutive cylinders also having flat tops or caps.

25 Minor features of my design comprise caps at the upper ends of and diametrically smaller than the diminutive cylinders, a skeleton band encircling the large cylinder and the other cylinders, a door at the lower end of the large cylinder having a handle and a beveled end, an arm projecting from the large cylinder at 30 the beveled end of the door, a knob at the apex of the conical or arched cap, a bunch of flowers upon the large cylinder and above the other cylinders, and a branch of a rose-tree bearing a blossom upon the large cylinder be- 35 low the other cylinders.

Referring now to the drawing in detail, the numeral 1 designates the large cylindrical body.

2 designates the cylindrical bodies which flank the large cylindrical body. 40

3 designates the diminutive cylindrical bodies arranged concentrically of the front side of the large cylindrical body and between the cylindrical bodies 2.

4 designates the skeleton band encircling 45 the large cylindrical body.

5 designates the conical or arched cap at the upper end of the large cylindrical body 1, and said cap is concentrically fluted or corrugated, as shown at 6, and provided at its 50 apex with the knob 7.

8 designates the flat tops of the cylinders 2 and the flat tops of the diminutive cylinders.

9 designates the small cylindrical caps of 55 the diminutive cylinders.

10 designates the door, having the upper corner at its free end cut away or beveled.

11 designates the handle of the door.

12 designates an arm projecting from the cylinder 1 from one end of an elongated figure 60 13 thereof.

What I claim is—

The design for a chest or bin, as shown and described.

In testimony whereof I affix my signature 65 in the presence of two witnesses.

MILLARD F. BROWN.
